ESLI A. MARSH, OF CHICAGO, ILLINOIS, ASSIGNOR TO J. F. ELAM SALES SERVICE, INC.,
OF CHICAGO, ILLINOIS, A CORPORATION OF ILLINOIS.

MACHINE FOR FEEDING AND PACKING PULVERULENT MATERIAL.

Application filed May 14, 1925. Serial No. 30,255.

The machine of the present invention is intended as an embodiment, in improved and developed form, of the packer bars shown and described in my Patent No. 1,487,683, issued March 18, 1924. This patent shows and describes the use of stepped packer bars which are designed to act in conjunction with one another in the feeding and packing of flour or other semi-free flowing material which necessitates the use of some form of mechanical agitating and packing means in order to cause a free and uniform flow of the material from a bin or receptacle into the bags or packages located in position to be filled.

The present invention utilizes packer bars similar in general construction and principle of operation to those described in the above mentioned patent, but differing somewhat in form in order to more perfectly effect the objects in view; and the present invention further relates to the embodiment of such improved packer bars in a complete machine so designed and constructed as to meet the requirements of rapid, certain and uniform operation in the delivery of such materials as flour or the like into bags or packages.

Further objects and purposes of the invention will appear from a detailed description thereof, with reference to the accompanying drawings, wherein—

Figure 1 is a front elevation of the entire machine;

Fig. 2 is a side elevation thereof;

Fig. 3 is a detail of the cranked driving shaft for the packer bars;

Fig. 4 is a sectional elevation taken through the center of the machine;

Fig. 5 is a perspective view of one of the improved packer bars of the present invention; and

Fig. 6 is a sectional detail of the spout and packer bars.

The machine as a whole consists of side standards 10 which are mounted upon a base 11 and extend upwardly to such height as to afford a suitable support for the feeding and packing mechanisms within convenient reach of the operator.

The standards 10 afford a mounting for a discharge chute 12 leading from a bin or conveyor 13 located behind the standards, the discharge chutes extending forwardly

and downwardly and connecting with an elbow 14 which discharges into a funnel 15, which funnel, at its lower or diminished end, connects with a rectangular feed spout 16. The arrangement of the chute, elbow and funnel is such as to afford an unobstructed passage for the downflow of the flour or other similar material.

The elbow, as shown, is connected with the lower end of the chute in such a way as to divert the pulverulent material from an oblique downflow to a vertical downflow into and through the spout which directly coats with the bags or receptacles, which are preferably of rectangular formation to fit snugly around the exterior wall of the spout, which spout, while the bag is being filled, enters directly into the mouth thereof, as indicated by dotted lines in Fig. 4.

The upper wall of the elbow 14 is perforated with a pair of guide sleeves or bosses 17, through which are entered a pair of reciprocating plunger rods 18, to which are pivoted a pair of connecting rods 19 which engage with cranks 20 on an overhead driving shaft 21 which is carried by journal boxes 22 which are secured to the standards 10 near their upper ends. A pulley 23, acting through the medium of a clutch 24, serves to impart rotation to the driving shaft, which rotation causes a reciprocation of the plunger rods 18.

Each of the plunger rods 18 has secured to its lower end a packer 25, which packers, in conjunction with one another, afford the active elements for feeding down and packing the pulverulent material in general conformity with the principle of operation set forth in my Patent No. 1,487,683.

Each packer comprises a vertically elongated bar 26, the backs of which rest in flatwise contact with the adjacent flat front 95 and rear walls of the chute 16, which chute, as stated, is of rectangular oblong formation with its major dimension in transverse relation to the machine.

Each bar 26 is provided throughout its lower portion with a plurality of packer teeth 27 located in spaced relation to one another, each tooth being of wedge shaped formation and of transverse dimensions greater than the width of the packer bar. 105 The rear wall of each tooth lies within the

plane of the rear face of the bar 26, as indicated in Fig. 6, so that the rear or non-acting surface of each packer will lie in close contact with the adjacent front or rear wall of the chute, and the individual packer teeth are of transverse dimensions substantially equal to the width of the chute, so that the side faces 28 of the teeth will shut against the proximate side walls of the chute and in position to carry down the pulverulent material tending to pack against such side walls.

The packer teeth being of greater width than the bar 26 will afford outstanding 15 wedge shaped shoulder portions 29, whose inner faces slope downwardly and inwardly and merge into the obliquely disposed acting inner faces 30 of the teeth. Each tooth presents its lower or packing face 31 at an 20 abrupt angle to the packer bar 26, and these packing faces, in conjunction, present a stepped formation, the teeth, however, being entirely separated from one another by intermediate portions of the packer bar. The 25 packer bar merges into and terminates with the lowermost teeth, the lower or packing face of which is unbroken by a further extension of the bar.

Each bar is provided on its inner face 30 with a longitudinally extending centrally disposed spline or rib 32 which serves the double function of reinforcing the bar and also serving to divert the pulverulent material laterally onto the sloping inner faces 35 of the teeth. It is preferred to make each packer bar with its quota of teeth of cast or integral formation, and the dimensions of the teeth are such that the packing face of each tooth will present an area substantially equal to one half of the cross sectional area of the spout, so that, when oppositely facing teeth are brought into juxtaposed position, the lower inner edges of the teeth 40 will lie in close relation to one another, only sufficient clearance being afforded to permit the packer bars to reciprocate without interference.

The spout with its packer bars co-operates 50 with a platform 33 which is mounted upon a plunger rod 34 entered through a table 35, which affords a working space for the operator and is preferably located about three feet from the floor. The lower end of the plunger 34 is secured to a sliding cross bar 36, the ends of which are provided with sleeves 37 slidably mounted upon a pair of vertical guide rails 38 which extend between the base 11 and the table 35. The arrangement is such that as the sliding cross bar 36 55 is lifted it will project the platform 33 upwardly toward the mouth of the spout to bring the empty bag into co-operative relation to the spout at the beginning of the filling operation.

60 Means are provided for yieldably support-

ing the platform in elevated relation, so that the platform will be progressively depressed by the pressure of the accumulating charge of material downflowing into the bag or receptacle. Such means will now be described.

The sliding cross bar 36 has secured thereto a length of chain or cable 39, the upper end of which is secured by a clip 40 to the rim of the sprocket wheel 41 keyed to a weight shaft 42. The shaft also has keyed thereto a smaller sprocket 43 which meshes with a weight chain 44 carrying a weight 45 at its outer or free end. The opposite end of the weight chain is secured to a crank arm 46 mounted upon the end of a rock shaft 47, which shaft, at its forward end, is provided with an inwardly extending foot treadle 48. By depressing the foot treadle the rock shaft is rotated to bring the crank arm 46 into downwardly extending relation, which imparts a down pull to the lower end of the weight chain and thereupon elevates the weight and concurrently rotates the weight shaft 42 with the large sprocket 41 mounted thereon. This slackens the depending end of the chain 39 and allows a lowering by gravity of the sliding cross bar 36 and serves to lower the bag carrying platform 33.

When the treadle is released the platform will automatically rise toward the spout, and when down pressure is exerted by the charge of material flowing into the bag the platform will be progressively depressed against the pressure afforded by the weight until the bag has been completely filled.

The gear arrangement is one whereby a relatively slight movement of the weight will control a relatively greater movement of the platform, which is desirable in the rapid and uniform operation of the machine.

It is desirable to provide means for stopping the feeding operations of the packer bars as soon as the bag has been filled to the desired height, and such means will now be described.

Immediately in front of the plunger rod 34 is located a swinging frame bar 49 which is hinged, at its lower end, to a pin 50 in such a way as to permit limited swinging movement of the upper end of the bar. The swinging bar is provided with an elongated slot 51 (see Fig. 1) which affords a guideway for an adjusting block 52 carrying a cam face 53 on its rear side. The block 52 has entered therethrough an adjusting screw 54 which is rotatably mounted in upper and lower bearing blocks 55 and 56, and the screw is provided at its upper end with a hand wheel 57 preferably located above the surface of the table 35, so that the operator, by turning the hand wheel 57, may regulate the vertical position of the block 52 with 110 the cam 53 carried thereby.

The plunger rod 34 is provided on its front face with a boss 58 which coacts with the cam 53, the arrangement being such that as the plunger rod is lifted by the action of 5 the weight 45 the boss 58 will engage the cam 53 and swing the bar 49 forwardly throughout the interval during which the boss is riding across the cam face. After 10 the boss has passed the cam face, the swinging bar 49 will be restored to its normal position by the action of a coil spring 59 which encircles the rod 60 extending forward from the upper end of the swinging bar and through a bracket 61 against which 15 the outer end of the spring contacts.

The swinging bar is provided, near its upper end, with an inwardly extending latch tooth 62 having an abrupt upper face which is adapted, when the swinging bar is thrust inwardly, to underlie the end of a lever arm 63 which is pivoted near its center to a bracket 64, and is provided at its outer end with an enlarged head 65 which embraces a clutch operating rod 66 adapted to control 25 the movements of the clutch 24.

The inner end of the lever 63 is adapted, at the proper time, to be lifted by the contact of a stop lug 67 carried by the plunger rod 34, the arrangement being such that 30 when the plunger has been moved upwardly by the weight to the required distance to bring the mouth of the bag around the lower end of the chute 16 the lug 67 will engage with the under edge of the inner end of the lever 63 and lift the same, thereby depressing the outer end of the lever and causing the lever head 65 to engage with a collar 68 on the clutch rod 66 which draws down the clutch rod against the tension of a spring 40 69, thereby engaging the clutch and initiating the rotation of the crank shaft 21. Thereupon the packer bars will begin to work in feeding and packing down the material into the bag, which will cause the platform and plunger 34 to be lowered against the action of the weight.

The lifting of the inner end of the lever 63 by the lug 67 will cause the inner end of the lever to be engaged by the latch lug 62, 50 which then will spring inwardly so that the inner end of the lever will be held elevated during the time required to fill the bag to the desired degree, but as soon as the plunger rod has been depressed sufficiently 55 to bring the boss 58 into engagement with the cam 53, a further lowering of the plunger 34 will cause an outswing of the bar 49, which carries the latch tooth 62 away from the lever 63, thereby releasing the lever and allowing the clutch rod to rise under 60 spring tension, which disengages the clutch and suspends the operation of the packers. The clutch is so arranged that the packing 65 operation will come to a halt with the packer teeth in opposed relation to one an-

other, so that the spout will be closed against further discharge of material. Thereafter, the platform can be additionally depressed by pressing down on the foot treadle as in Fig. 1, which further elevates the weight 70 and permits the platform and associated parts to descend by gravity. With the platform in its lowermost position, the bag with its contents can be readily removed and an empty bag positioned.

By adjusting the position of the cam 53, the clutch can be thrown out at any desired point during the descent of the platform, which permits the operator to adjust the device to bags of varying depth or capacity.

The formation of the packer bars is such as to afford to the lower or packing surfaces of the teeth a maximum packing surface, which is attained by laterally extending the teeth beyond the edges of the connecting 85 packer bar and carrying the sloping inner surfaces of the teeth back to the plane of the rear surfaces of the bars. This brings the wedge shaped shoulders 29 into direct contact with the front and rear walls of the 90 spout, so that they will serve to scrape off and inwardly divert any of the pulverulent material which may tend to adhere to the walls of the spout. The arrangement of the teeth, furthermore, is better adapted to afford the necessary agitation than that afforded by the teeth of the formation shown in my Patent No. 1,487,683. Furthermore, the separation of the teeth one from the other 95 avoids the provision of sharp inner angles or corners beneath the teeth into which the pulverulent material may tend to lodge and pack, and by proportioning the teeth in such a way that each tooth will present its major 100 dimension from side to side of the chute 105 the dimensions of the teeth from back to front may be correspondingly lessened without reducing the packing area, which constitutes a more desirable arrangement than one in which the depth of the teeth is 110 greater, since relatively shallow teeth tend 115 better to divert and direct the material down through the center of the spout.

The machine as a whole is one which enables the bags to be rapidly, evenly and uniformly filled and packed and the filled bags to be removed and replaced by empty bags in a speedy and efficient manner; and the arrangement for stopping the operation of the packers at a predetermined point insures uniform filling and prevents any waste of material due to a dribbling from the spout after the bag has been filled to the desired point, since the packer teeth, when in opposed relation, serve the purpose and function of a valve closure to prevent further discharge of the material.

Although the machine has been described with particularity as to detail, it is not the intention to unduly limit the invention, since 130

modifications in structure may be made without departing from the spirit of the invention.

I claim:

- 5 1. In a machine for feeding and packing pulverulent material, the combination of a spout, a packer bar within the spout, said packer bar having downwardly projecting teeth in separated relation to one another, 70
10 an opposing member having similarly positioned downwardly projecting teeth, and means for reciprocating the packer bar, the edges of the opposed teeth lying in close relation to one another when in the medial position, substantially as described. 75
- 15 2. In a machine for feeding and packing pulverulent material, the combination of a spout, a packer bar within the spout, said packer bar having downwardly projecting teeth in separated relation to one another, an 80
20 opposing member having similarly positioned downwardly projecting teeth, and means for reciprocating the packer bar, the edges of the opposed teeth lying in close 85
25 relation to one another when in the medial position, and the teeth of one of said cooperating members being configured to project laterally beyond the edges of said member, substantially as described. 90
- 30 3. In a machine for feeding and packing pulverulent material, a packer bar provided with a plurality of downwardly projecting wedge shaped teeth each affording an abrupt packing face and a sloping feeding face, 95
35 the teeth projecting laterally beyond one edge of the packer bar, substantially as described. 100
- 40 4. In a machine for feeding and packing pulverulent material, a packer bar provided with a plurality of downwardly projecting wedge shaped teeth each affording an abrupt packing face and a sloping feeding face, the teeth projecting laterally beyond one edge of the packer bar, and the feeding face sloping upwardly and rearwardly to a knife edge, 105
45 substantially as described. 110
- 50 5. In a machine for feeding and packing pulverulent material, a packer bar provided with a plurality of downwardly projecting wedge shaped teeth each affording an abrupt packing face and a sloping feeding face, the teeth projecting laterally beyond one edge of the packer bar, and the feeding face sloping upwardly and rearwardly to a knife edge lying flush with the rear face of the packer bar, substantially as described. 115
55
- 60 6. In a machine for feeding and packing pulverulent material, a packer bar provided with a plurality of downwardly projecting wedge shaped teeth each affording an abrupt packing face and a sloping feeding face, the teeth projecting laterally beyond one edge of the packer bar, the individual teeth being separated from one another, substantially as described. 120
65
7. In a machine for feeding and packing pulverulent material, a packer bar provided with a plurality of downwardly projecting wedge shaped teeth each affording an abrupt packing face and a sloping feeding face, 70
75 the teeth projecting laterally beyond one edge of the packer bar, and the feeding face sloping upwardly and rearwardly to a knife edge, the individual teeth being separated from one another, substantially as described. 75
8. In a machine for feeding and packing pulverulent material, a packer bar provided with a plurality of downwardly projecting wedge shaped teeth each affording an abrupt packing face and a sloping feeding face, 80
85 the teeth projecting laterally beyond one edge of the packer bar, and the feeding face sloping upwardly and rearwardly to a knife edge lying flush with the rear face of the packer bar, the individual teeth being separated from one another, substantially as described. 90
9. In a machine for feeding and packing pulverulent material, a packer bar provided with a plurality of downwardly projecting wedge shaped teeth each affording an abrupt packing face and a sloping feeding face, the teeth projecting laterally beyond one edge of the packer bar, the individual teeth being separated from one another, and a rib extending inwardly from the inner face of the packer bar and between the separated teeth, substantially as described. 95
95
10. In a machine for feeding and packing pulverulent material, a packer bar provided with a plurality of downwardly projecting wedge shaped teeth each affording an abrupt packing face and a sloping feeding face, the teeth projecting laterally beyond the edge of the packer bar, and the feeding face sloping upwardly and rearwardly to a knife edge, 105
105 the individual teeth being separated from one another, and a rib extending inwardly from the inner face of the packer bar and between the separated teeth, substantially as described. 110
110
11. In a machine for feeding and packing pulverulent material, a packer bar provided with a plurality of downwardly projecting wedge shaped teeth each affording an abrupt packing face and a sloping feeding face, the teeth projecting laterally beyond one edge of the packer bar, and the feeding face sloping upwardly and rearwardly to a knife edge lying flush with the rear face of the packer bar, the individual teeth being separated from one another, and a rib extending inwardly from the inner face of the packer bar and between the separated teeth, substantially as described. 115
115
12. In a machine for feeding and packing pulverulent material, the combination of a spout configured to receive the open end of a sack, a packing member within the spout, a shaft and connections for impart- 120
125

- ing packing movements to the packing member, a constantly rotating driving member, a clutch for imparting rotation from said driving member to the shaft, a vertically movable platform beneath the spout, means operated by the vertical movements of said platform for automatically throwing said clutch into and out of clutching relation, a weight tending to lift the platform toward the spout, a sprocket chain to the outer end of which said weight is secured, a relatively small sprocket wheel over which said sprocket chain is carried, a weight shaft upon which said sprocket wheel is mounted, a relatively large sprocket wheel mounted on the weight shaft, and a sprocket chain connected at one end to the larger sprocket wheel and at its other end to the platform substantially as described.

13. In a machine for feeding and packing pulverulent material, the combination of a spout configured to receive the open end of a sack, a packing member within the spout, a shaft and connections for imparting packing movements to the packing member, a constantly rotating driving member, a clutch for imparting rotation from said driving member to the shaft, a vertically movable platform beneath the spout, means operated by the vertical movements of said platform for automatically throwing said clutch into and out of clutching relation, a weight tending to lift the platform toward the spout, a flexible connection to the outer end of which said weight is secured, a relatively small wheel over which said flexible connection is carried, a weight shaft upon which said wheel is mounted, a relatively large sprocket wheel mounted on the weight shaft, a flexible connection connected at one end to the larger wheel and at its other end to the platform, and means controlled by the operator for drawing on the end of the weight connection opposite to the weight to lift the weight and permit the platform to descend by gravity, substantially as described.

14. In a machine for feeding and packing pulverulent material, the combination of a spout configured to receive the open end of a sack, a packing member within the spout, a shaft and connections for imparting pack-

ing movements to the packing member, a constantly rotating driving member, a clutch for imparting rotation from said driving member to the shaft, a vertically movable platform beneath the spout, means operated by the vertical movements of said platform for automatically throwing said clutch into and out of clutching relation, a weight tending to lift the platform toward the spout, a sprocket chain to the outer end of which said weight is secured, a relatively small sprocket wheel over which said sprocket chain is carried, a weight shaft upon which said sprocket wheel is mounted, a relatively large sprocket wheel mounted on the weight shaft, a sprocket chain connected at one end to the larger sprocket wheel and at its other end to the platform, and a foot treadle and connections for imparting a tension to the weight chain to lift the weight and permit the platform to descend by gravity, substantially as described.

15. In a machine for feeding and packing pulverulent material, the combination of a spout configured to receive the open end of a sack, a packing member within the spout, a shaft and connections for imparting packing movements to the packing member, a constantly rotating driving member, a clutch for imparting rotation from said driving member to the shaft, a vertically movable platform beneath the spout, means operated by the vertical movements of said platform for automatically throwing said clutch into and out of clutching relation, a weight tending to lift the platform toward the spout, a flexible connection to the outer end of which said weight is secured, a relatively small wheel over which said flexible connection is carried, a weight shaft upon which said wheel is mounted, a relatively large sprocket wheel mounted on the weight shaft, a flexible connection connected at one end to the larger wheel and at its other end to the platform, and means for drawing on the weight connection to lift the weight and turn the wheels for lowering the platform, substantially as described.

16. In a machine for feeding and packing pulverulent material, the combination of a spout configured to receive the open end of a sack, a packing member within the spout, a shaft and connections for imparting pack-

ESLI A. MARSH.
